HARRISON L. RAKESTRAW, OF TOLEDO, OHIO.

CARBURETER.

1,140,064.

Specification of Letters Patent.

Patented May 18, 1915.

Application filed February 7, 1914. Serial No. 817,138.

To all whom it may concern:

Be it known that I, HARRISON L. RAKESTRAW, a citizen of the United States of America, residing at Toledo, Lucas county, Ohio, have invented a new and useful Carbureter, of which the following is a specification.

This invention relates to vaporizing a liquid.

10 This invention has utility when adapted to forming fuel gas by the commingling of a liquid and air, and as disclosed herein may be readily used for carbureting gasoline or kerosene, or different hydrocarbons of widely 15 different properties.

Referring to the drawings, Figure 1 is a medial vertical section through a carbureter embodying features of the invention; Fig. 2 is a section on the line II-II, Fig. 1, looking in the direction of the arrow; Fig. 3 is a fragmentary view, on an enlarged scale of the cam controlling the by-pass duct; and Fig. 4 is a section on the line IV-IV, Fig. 1, looking in the direction of the arrow.

25 The duct 1, for fuel supply, say gasoline, is in communication through the passage 2 (Figs. 1, 4) in the valve 3 with the upwardly extending passage 4 in the valve 3. The valve 3 may be shifted by the arm 5 from the supply passage 1 to cut off said 30 passage 1 and be in communication with the passage 6, say supplying kerosene, or a less easily carbureted hydrocarbon than is supplied by the passage 1. The handle 5 permits of ready control of the three-way 35 valve 3.

The valve passage 4 has its communication with the fuel supply passage 7 controlled by the needle valve 8 mounted on the 40 lever 9 carrying the float 10 in the reservoir 11 in communication by the passage 12 with the passage 7. The float 10, through the valve 8 maintains a constant level of fuel in the reservoir 11 and passage 7.

45 The fuel is removed by injector action for the carbureting through the duct 13, which has the needle valve 14, which may have its degree of opening accurately controlled by the cam 15 provided with the bolts 16 swivelled in the shoe or adjustable cam face 17. By shifting the arm 18 through the link 19,

the position of the cam 15 may be such as to allow the spring 20 to hold the valve needle 14 in the proper clearance as to the passage 13 for allowing the desired liquid fuel supply to pass as determined for the various positions of the cam.

55 The passage 13 by-passes the reservoir 11 and is in direct communication with the entrance to the passage 7, permitting this passage 13 at once to receive the character of fuel with which the arm 5 has placed the valve 3 in communication, and conduct such liquid fuel to be sprayed immediately by the spreading tubular jets 21 in the upward 60 flow of the primary air supply from the duct 22 in the upwardly extending passage 23 passing centrally through the reservoir 11 to the fuel or mixing chamber. The fuel dispersing jets 21 tend to subdivide the 65 liquid to such an extent throughout the in-rushing air that complete atomization is approached.

A supply for a heating medium is 75 conveniently available in the form of internal combustion engine exhaust having the passage 25 provided with the enlargement 26 therein jacketing the chamber 24 in its travel to its outlet section 27. The chamber 24 has the inward and downwardly extending 80 heat conducting and liquid draining baffles 28, which are alternately oppositely inclined. The warmed walls of the chamber 24 keep these baffles 28 heated, and any liquid particles adhering thereto are warmed 85 to approach vaporization temperature. Should vaporization not be thus effected, the accumulated liquid in running down the baffles approaches the high velocity vapor stream and in falling into the volume there- 90 of has its vaporization made certain. The undercut continuous edges 29 of the walls of the chamber 24 and passage 23, like the baffles 28 conduct any condensation into the air or gas stream volume to be re-vaporized.

95 Between the reservoir 11 and the chamber 24 is the heat insulation packing 30 reducing the tendency toward vaporization of the liquid fuel in the reservoir 11, thereby avoiding loss from this source as well as fluctuation 100 in the float control due to gravity change.

The flow of the fuel from the mixing or

fuel chamber 24 may be controlled by the controllable valve or throttle 31 which may be in communication with the cylinders of internal combustion motors for the drawing of the fuel supply therefor.

In starting a motor, an easily combustible mixture may be desired, and the more readily carbureting supply may be selected by the valve 3. That the mixture may be rich, only the primary air supply 22 may be used. As the motor gets under way and heated up, the less readily vaporized fuel may be used. To decrease the richness of the fuel mixture, a secondary air supply 15 may be admitted by so shifting the lever 32 as to allow the disk 33 to rise that the spring 34 may permit the valve 35 to unseat at the suction through the chamber 24, and draw in a further air supply by way of the 20 passage 36 in communication with the plurality of parallel tubes 37 jacketed to be heated by the exhaust and then delivered to the chamber 24. By cupping the valve 35, it may unseat some distance before clearance for any appreciable air intake occurs, thereby avoiding chatter in operation.

The carbureter as herein disclosed, is simple in its structure, capable of use with widely varying character of fuel or fuels, 30 for easy and economical operation.

In the operation of the throttle 31, the fuel intake valve 14 may to advantage be controlled simultaneously by the shifting of the cam 15 to let in more fuel as the throttle 35 31 uses more mixed charge from the chamber 24.

The central sleeve 38 of the valve disk 35 guides the disk in its reciprocations along the rod 39, while adjusting the nut 40 40 may through the disk 33 fast on the stem 39 vary the seating force of the spring 34 as may be desired in normal running in-

dependently of the cut out of this air supply by the lever 32.

What is claimed and it is desired to secure by Letters Patent is:

1. A carbureter embodying a centrally disposed upwardly opening fuel supply passage, an air supply passage thereabout for initially bringing the fuel into suspension, 50 a chamber to which said passages deliver, said chamber provided with baffles inwardly and downwardly extending, the undersides of said baffles upwardly extending from central of the chamber, each lower baffle having its free edge overlapped by the drip edge of the next baffle above, whereby any condensation and liquid is directed to flow away from the chamber wall and off the baffles into a tortuous incoming gaseous mixture 60 current, and heating means enveloping the chamber walls from which the baffles extend for heating the baffles and facilitating complete vaporization.

2. A carbureter embodying a fuel supply 65 passage, a reservoir, a float in said reservoir, a float actuated valve in said passage controlling the supply to said reservoir, a plurality of fuel supply ducts for said passage, control means for selecting the duct 70 to supply the passage, an air supply passage, and a fuel by-pass duct direct from the valve to the air supply passage.

3. The combination in a carbureter of a float reservoir and a mixing chamber, of 75 heating means for the chamber, and a heat insulating partition between the chamber and reservoir.

In witness whereof I affix my signature in the presence of two witnesses.

HARRISON L. RAKESTRAW.
